Frank J. Stuart,

UNITED STATES PATENT OFFICE.

FRANK J. STUART, OF ST. LOUIS, MISSOURI.

ABDOMINAL APPLIANCE.

Application filed March 25, 1921. Serial No. 455,532.

The invention has for an object to effect improvements in the functional qualities of surgical belts and abdominal supports. It is also a purpose to improve wearing qualities and add to the comfort of the wearer, while still attaining security in the positioning and retention of the garment in proper place upon the person. It is an especial aim to provide means to prevent an abdominal belt from shifting downwardly upon the person and prevent it from slipping upwardly, without using straps which will interfere with the anus or other organs thereadjacent, nor involve liability of soiling of the garment or its retaining parts. In attaining these ends, structural difficulties have been encountered, and it is an object of the invention to provide a satisfactory construction whereby these difficulties are overcome, having a view to avoiding distortion of the device abnormally from the ideal contours which might reasonably be expected to be maintained in various cases where the wearing of my garment is involved. An important aim of the invention is to present a supporting garment which will permit and induce natural exercise of abdominal and other muscles, strengthening them and maintaining ideal positions or contours.

Additional objects, advantages and features of invention will appear from the combination and relation of structural parts as hereinafter described and shown in the drawings embodying my invention, wherein,

Figure 1 is a front view of my garment in use,

Figure 2 is a rear view thereof,

Figure 3 is an inside view of the device opened out.

There is illustrated a belt or support comprising a specially woven elastic fabric part 10, in which the elastic rubber or other strands 10' extend transversely horizontally so as to partly encircle the body when worn, the central part of this elastic part 10 being the front of the garment and being intended to be adjusted centrally over the abdomen with its lower edge portion closely adjacent the lower boundary of the iliac region. The section 10 has the elastic elements each of which as usual runs continuously from one end to the other of the fabric 10 more widely separated at the central part than adjacent the ends, so that the elastic portion is broader in the middle part than at the ends, and by reason of the lesser compres-

sive effect to the unit of surface which is progressively less from the ends toward the middle, the abdomen is caused to assume a more properly rounded and symmetrical form contributing to healthy and normal conditions of development in many different kinds of cases. This structure diminishes any tendency to crowd the abdominal contents upwardly toward the stomach and chest. The elastic part is formed with an upper and lower border 11 and 12 in which the elastic fibers are more closely spaced than in the medial portion, so that the belt has strength at the edges to prevent sagging or distortion, which would occur if the elastic element were even in strength throughout the breadth of the elastic part. Secured upon the upper edge of the elastic element 10, there is an openly woven or knitted fabric portion 13, in which a slip cord 14 is introduced, having its ends secured at respective ends of the belt, its central part extending outwardly through eyelets 15 at the front outer side of the garment. This is utilized to form a non-elastic upper edge on the belt which will be adjustable to accommodate the device readily to various waist measurements. Across the ends of the elastic portion 10 and the portion 13, there are secured non-elastic terminal pieces 16 of triangular form in the main, broader at the lower part than at the top, the elastic portion 10 having its lower edge aligned with the lower edges of the terminal pieces 16. In practice the bottom edges of the pieces 16 are made from four to six inches in length, thus affording a very wide part for attachment of that part of the leg pieces which is most effective in retaining the belt against slipping upward. The form of the terminal pieces is such that when the device is adjusted upon the wearer, the end edges will readily fall into or nearly into parallel relation, as shown in Fig. 2. Each terminal piece is eyeleted adjacent its outer vertical edge to receive a suitable lacing 17, and a moderate stiffening of whale bone or other suitable material is incorporated in the pieces, as indicated at 18.

Leg pieces 19 are attached to the lower edge of the garment, which are formed of a suitable knitted or other fabric adapted to readily accommodate itself snugly to the upper portions of the limbs of the wearer. These leg portions have their upper parts cut away at the inner sides, forming crotch

engaging edges in the manner indicated at 20 in Fig. 3, so that only the outer side portions of the legs extend fully up to the belt body, and when the device is adjusted upon a person the upper edge portions of the leg elements at the inner sides of the limbs extend upwardly and outwardly so that a considerable space is provided between the points of their junction with the belt both 10 at front and rear, the space being considerably greater at the rear than at the front. It should be noted that the crotch edge 20 of the leg piece at the rear is connected to the piece 16 intermediately of its width, so 15 that for a considerable distance toward the hips the lower part of the belt cannot slip upwardly relatively to the point of connection owing to the tendency of the non-elastic material to oppose such distortion. 20 Yet there is elasticity in the belt proper thereabove. It should also be considered that while the pieces 16 limit the elasticity of the belt at the back this limitation is progressively less from the bottom, where 25 practically no expansion and contraction is necessary in the back, toward the top, where elasticity is desirable in order not to confine the waist unduly. In attaching retaining elements to the lower edge of such a belt at 30 widely different points, as indicated at 21 in Fig. 1, where the body of the elastic material immediately adjacent is subjected to even pressure, the intervening part between the two leg elements will tend to yield and 35 bulge outwardly, causing a distortion of the abdomen which would involve a serious deformation in obstetrical cases, or possibility of rupture or other lesions in other cases. It is not practicable to use a non-elastic 40 element to bridge this gap, as there would then be presented against the abdomen an area without local elasticity which would be irksome to the wearer, and also involve greater compression of the immediately confined parts. I have found that the belt at 45 unsupported parts may be caused to retain its proper form with adequate elasticity by the use of a section of elastic of slightly greater tensile strength than the parts 11 and 12, as indicated at 22 where a portion 50 of such elastic is provided on the section 10 along its lower edge and overlapping that edge, the upper cut away edge portion of the leg elements terminating at respective 55 ends of the elastic 22, to which the said edge portions 20 are directly attached by suitable non-elastic terminal pieces 23. The edge portions 20 are suitably bordered with non-elastic material, as illustrated whereby secure retention of the device is facilitated. 60 The edge portions 20 at the rear part of the

device are attached to the lower edge of the belt body intermediately of the bases of the non-elastic terminal elements 16. When the device is worn, the leg elements 19 fit snugly 65 upon the limbs of the wearer and with the belt body form a continuous smoothly fitting garment extending upwardly over the outer sides of the hips and forwardly upon the abdomen. The edge portions 20 with their 70 reinforcements engage securely in the crotch of the wearer but with sufficient spacing between their proximal parts to assure comfort, ventilation, and ease of the wearer in all respects, while at the same time securely 75 retaining the appliance against slipping upwardly or downwardly out of position and enabling it to maintain a firm evenly distributed pressure over the entire abdomen holding all parts securely and as nearly as 80 possible in ideal form.

In the wearing of this garment the muscles of the abdomen are permitted to expand at each inspiration of the breath, as in nature. But, whereas the unsupported muscles 85 might by reason of excessive strain, distortion, lack of contractibility, or because the tissues are scar tissues, fail, to return promptly to initial position, and would then be still somewhat abnormally distended 90 from their natural state, when my garment is used it will gently and firmly force the muscles to return to their initial positions, thus bringing about a prompt recovery of 95 those muscles and also supplementing their action aiding them by stimulation to immediately approach as nearly as practicable to the natural form and state. By thus obtaining an active expansile, and contractile condition at the surface, atrophy is obviated 100 and the enforced exercising of the muscles will strengthen them and bring them back to normal condition enabling them to be self sustaining finally.

What is claimed is:

In an abdominal garment for the purposes indicated, a supporting webbing adapted to cover substantially the entire abdomen and comprising a webbing elastic principally by extension of the horizontal dimension of the belt, and consisting of transverse elastic threads woven with vertical threads so as to be divergent from the ends toward the middle, whereby the compressive effect per unit of area is progressively and continuously less from said ends toward the middle, and means to secure the web upon the person, including means to adjust the tension.

In testimony whereof I have affixed my 120 signature.

FRANK J. STUART.
